US0D1084651S

(12) **United States Design Patent** (10) **Patent No.:** **US D1,084,651 S**
(45) **Date of Patent:** **** Jul. 22, 2025**

(54) **HOLSTER**

(71) Applicant: **Safariland, LLC**, Jacksonville, FL (US)

(72) Inventors: **Matthew McKendrick**, Jacksonville, FL (US); **Dylan Vaccaro**, Jacksonville, FL (US)

(73) Assignee: **Safariland, LLC**, Jacksonville, FL (US)

(**) Term: **15 Years**

(21) Appl. No.: **29/851,465**

(22) Filed: **Aug. 29, 2022**

(51) LOC (15) Cl. **03-01**

(52) U.S. Cl.

USPC **D3/222**

(58) **Field of Classification Search**

USPC D3/201, 207, 215, 220-223, 254, 262, D3/267, 273, 300, 303, 318, 321, 327, D3/328, 212, 224, 228, 259, 315, 226, D3/269, 304; D22/199

(57) **CLAIM**

The ornamental design for a holster as shown and described.

DESCRIPTION

FIG. 1 is a face side perspective view of a holster
FIG. 2 is a body side perspective view of the holster of FIG. 1;
FIG. 3 is a face side elevational view of the holster of FIG. 1;
FIG. 4 is a body side elevational view of the holster of FIG. 1;
FIG. 5 is a top plan view of the holster of FIG. 1;
FIG. 6 is a bottom plan view of the holster of FIG. 1;
FIG. 7 is a back end view of the holster of FIG. 1; and,
FIG. 8 is a front end view of the holster of FIG. 1.
Subject matter shown in broken lines is unclaimed environment and forms no part of the claimed design.
The dash-dot-dash lines represent boundaries of the claimed design that form no part thereof.

1 Claim, 6 Drawing Sheets
